B. P. CORBAN, OF BRISTOL, CONNECTICUT.

Design No. 3,454, dated April 27, 1869.

DESIGN FOR A CLOCK-CASE FRONT.

The Schedule referred to in these Letters Patent and making part of the same.

To all whom it may concern:

Be it known that I, B. P. CORBAN, of Bristol, in the county of Hartford, and State of Connecticut, have originated and designed a new Design for a Clock-Case, of which the following is a full, clear, and exact description, reference being had to the accompanying drawing, making a part of this specification, which drawing is a front elevation of my design or invention.

The frame of the case A is formed into the form of a rhombus, or diamond, inside of which frame A rests the panel B.

The centre of the panel B has a round opening, to expose the dial C, which is encircled by the round sash D.

In each of the inside corners of the frame A, I place small diamond-shaped blocks a a' a'.

As the case is longer than it is wide, the diamond-shaped blocks a' a' are larger than the blocks a a, in order to have the corners of each about the same distance from the sash D.

The whole is combined and arranged as shown, to produce a cheap, tasty, and novel design for a clock-case front, which is well adapted to use as a case for marine clocks.

What I claim as my invention, and desire to secure by Letters Patent, is—

The design for a clock-case front, herein shown and described.

B. P. CORBAN.

Witnesses:

C. A. SHEPARD,
JAMES SHEPARD.
